ILLUMINABLE TELEPHONE SWITCH ATTACHMENT OR SIMILAR ARTICLE

Arthur L. Davenport, 5140 Avenida Hacienda,
Tarzana, Calif.

Filed Mar. 4, 1963, Ser. No. 33,800

Term of patent 14 years

(Cl. D26—14)

FIG. 1 is a perspective view of an illuminable telephone switch attachment or similar article showing my new design;

FIG. 2 is a front elevational view;

FIG. 3 is a side elevational view, the opposite side being substantially a mirror image thereof;

FIG. 4 is a top plan view;

FIG. 5 is a bottom plan view; and

FIG. 6 is a rear elevational view thereof.

The dominant features of my new design are shown in solid lines in the drawing, the fragmentary portion of a telephone front, right wall, and inset base being shown in dash-dot lines in FIG. 3 for illustrative purposes only.

A portion of the drawing figures is diagonally lined to indicate a light transmitting surface.

I claim:

The ornamental design for an illuminable telephone switch attachment or similar article, as shown and described.
